F. F. WOODS.

OPERATING DEVICE FOR VALVE GRINDERS.

APPLICATION FILED OCT. 19, 1916.

1,331,307.

Patented Feb. 17, 1920.

UNITED STATES PATENT OFFICE.

FRANK FERNANDO WOODS, OF WICHITA, KANSAS.

OPERATING DEVICE FOR VALVE-GRINDERS.

1,331,307.

Specification of Letters Patent.

Patented Feb. 17, 1920.

Application filed October 19, 1916. Serial No. 126,585.

To all whom it may concern:

Be it known that I, FRANK F. Woods, a citizen of the United States, residing at Wichita, in county of Sedgwick and State 5 of Kansas, have invented certain new and useful Improvements in Operating Devices for Valve-Grinders, of which the following is a specification.

This invention relates to an improvement 10 in valve-grinders for grinding the valves in gas, gasoline and similar engines.

Some of the objects accomplished are as follows:—

First, to provide a device that is effective 15 in operation;

Second, a machine that is simple in construction;

Third, to make a valve-grinder that will do rapid work, with a minimum amount of 20 labor.

Other objects of the invention will appear as the nature of the same becomes better understood.

In the accompanying drawings:—

25 Figure 1 is a side elevation of the complete device;

Fig. 2 shows the spindle detached; and

Fig. 3 is a sectional view of the handle, disclosing the ball thrust and a portion of 30 the spindle.

Fig. 4 is a detail view of the left-hand side of Fig. 1.

The frame 1 is preferably made of wire, as shown, although it may be made of flat 35 strip or other suitable material. The wire is coiled around to form the bearings 1^A and 1^B for a spindle 3, as well as the guide-rings 1^C and 1^D, through which the cord to be hereinafter mentioned passes.

40 The frame is made rigid by coiling one end portion around the other as shown at 1^E. A spool 2 is secured to spindle 3 by means of the pin 4. The handle 5 is bored to fit over the upper end of spindle 3. The upper 45 end of spindle 3 is provided with a groove 12, as shown. A key 6 passes through a hole in the handle and through the groove 12 at one side of the spindle 3 to prevent the handle becoming detached.

50 Mounted in the hole in the handle, and above the spindle, is a hardened steel ball 7. The lower end of spindle 3 is provided with a wrench of any suitable form to operate the valve shown in dotted lines. The wrench 55 8 is secured within the slot 13 in the spin-

dle 3 by the pin 9. It is so located as to permit a slight pivotal movement of the wrench 8.

The cord 10 passes around the spool 2, being secured at its ends to the ends of the 60 bow 11. The bow is formed into a hook 14 at one of its ends, and knots 15 are tied in the cord 10, so that the desired tension may be given the same.

To operate the device, the operator holds 65 the handle 5 in one hand, and the handle end 16 of the bow in the other. By moving the bow backward and forward, a rapid motion is imparted to spool 2, first in one direction and then in the other. 70

I claim:

1. A valve-grinder comprising a frame, a spindle journaled in the frame, a handle swiveled to the spindle, a bow and cord, the latter guided by the frame and wound about 75 the spindle, whereby the reciprocation of the bow imparts rotary motion to the spindle, and means for varying the tension of the cord.

2. In a valve-grinder, the combination 80 with a frame having oppositely-formed bearings and oppositely located guides therein, and a spindle journaled in the bearings, of a bow having a handle at one end and a hook at the other, and a cord secured to the 85 handle passed through the guides of the frame and around the spindle, and provided with means at one end whereby it is connected with the hook of the bow and its tension is regulated. 90

3. In a valve-grinder, the combination 90 with a frame having oppositely-formed bearings and oppositely-located guides therein, and a spindle journaled in the bearings, of a bow having a handle at one end and a hook at the other, a cord secured to the handle passed through the guides of the frame and around the spindle, and provided with means at one end whereby it is connected with the hook of the bow and its tension is 100 regulated, and a handle swiveled to one end of the spindle.

4. A valve-grinder comprising a frame, a spindle journaled therein, a handle having a socket portion telescoping one end of the 105 spindle, a ball between the end of the spindle and the socket, which telescopes the latter, the spindle circumferentially grooved within the socket of the handle, and a key extending through a hole in the handle and 110

into the groove in the spindle, whereby the handle is swiveled with a ball-bearing upon the end of the spindle.

5. In a valve-grinder, the combination with a frame, formed of a wire coiled to form bearings and guides, the ends of the wire secured together, of a spindle journaled in the bearings, a handle connected to the

end of the spindle, and a bow, the cord of which passes through guides in the frame 10 and is wound around the spindle, whereby to rotate the latter as the bow is reciprocated.

In testimony whereof I affix my signature.

FRANK FERNANDO WOODS
